UNITED STATES PATENT OFFICE.

FORREST D. LUCKEY, OF LOGAN, UTAH.

PADLOCK.

1,300,983.

Specification of Letters Patent. Patented Apr. 15, 1919.

Application filed August 9, 1918. Serial No. 249,074.

To all whom it may concern:

Be it known that I, FORREST D. LUCKEY, a citizen of the United States, and resident of Logan, in the county of Cache and State of Utah, have invented certain new and useful Improvements in Padlocks, of which the following is a specification.

This invention relates to the class of locks and latches, and more particularly to a novel 10 and improved padlock.

The invention has for its primary object the provision of an improved padlock having a novel key operated mechanism for releasing the shackle, the device being so constructed 15 as to prevent it from being operated by an instrument or piece of wire, and in fact, anything but with the proper key.

A further object of the invention is to provide an improved lock which is simple in 20 construction, economical to produce, strong and durable, and efficient in use.

With the above and other objects in view, as will appear as the description proceeds, the invention comprises the various novel 25 features of construction and arrangement of parts which will be more fully described herein and set forth with particularity in the claims appended hereto.

Reference is had to the accompanying 30 drawings forming a part of this application, in which like reference characters indicate the corresponding parts throughout the several views, in which

Figure 1 is a vertical sectional view of a 35 padlock constructed in accordance with my invention, the shackle being shown in a closed or locked position in connection with the parts associated therewith,

Fig. 2 is an edge elevation of the improved padlock,

Fig. 3 is a vertical sectional view, but showing the shackle released, with the parts in an unlocked position,

Fig. 4 is a detail view of the key employed 45 in the device,

Fig. 5 is a cross sectional view taken on the line 5-5 of Fig. 1, and

Fig. 6 is a cross sectional view taken on the line 6-6 of Fig. 1.

Referring to the drawings in detail, my 50 improved padlock is shown as comprising a casing 10 of rectangular formation, in its preferred embodiment, and comprising sections 11 and 12 fitted together and secured at 55 suitable points by rivets or dowel pins 13.

The casing sections are interiorly hollowed out sufficiently to accommodate the working parts, and as shown, a slot 14 is provided in one corner of the casing between the opposed sections, to pivotally receive one end of a 60 curved shackle 15, the pivot being designated 16 and the shackle being extended beyond the pivot and notched to receive one end of the usual form of opening spring 17 acting between the adjacent wall of the casing and the adjacent end of the shackle, as shown.

The free end of the shackle is beveled, as shown at 18, and provided with a transverse keeper or slot 19 running from its inner to 70 its outer edge, and said shackle enters a slot 20 also formed between adjacent sections of the casing at the edge opposite to the edge to which the shackle is pivoted and within the walls thereof.

Coöperating with the shackle in order to hold the same in a closed or locked position, is a catch or bolt 21 pivoted at its lower end, as shown at 22, and normally held into engagement at its upper end with the slot 19 80 through the medium of a tapered right angular engaging or nose portion 23, through the medium of a contractile spring 24 anchored to the casing and connected intermediately to the pivoted bolt or catch.

In order to withdraw the catch for permitting the shackle to spring open, thereby opening the padlock to release objects held thereby, there is provided a sliding block 25 having its upwardly extending portion 26 90 pivoted to the catch 21 above the spring 24 and a depending portion 27 serving as a supporting and guiding means within the casing. This block extends horizontally and is formed at its free end with a circular socket 28 receiving therein for rotation a barrel 29, which latter projects through the edge of the casing corresponding to that edge adjacent to which the shackle is pivoted, instead of to the opposite edge or at the bottom of the casing, as is usual, and is provided with a tortuous grooved slot 30 axially therethrough.

The barrel 29 is held against translation, through the medium of flanges or bumpers 31, the block 25 being correspondingly formed to engage the barrel, while the inner end of the latter is received within the socket 28 for rotation, being limited in this movement by a stop lug 32 projecting from the barrel 105 110

and engaging the casing or body of the lock.

The inner end of the barrel is spaced from the end wall of the socket 28 and through 5 said end wall a supplementary socket portion 33 of reduced diameter is formed, there being an undercut provided at diametrically opposite sides as shown at 34, communicating with the key receiving slot 35 in the 10 block 25, these undercut portions providing flanges 36 covering each one quarter area of the diameter while the remaining portions are solid so as to present flat faces whereby the key can only be turned in one direction, 15 namely to the right, and not to the left.

For this reason the key designated at 37 has its shank portion 38 tortuously grooved longitudinally to be properly received within the respective slots 30 and 35, it being 20 understood that the formation of the grooves can be varied so as to give a large number of combinations. The key shank 38 is formed with oppositely extending bit flanges 39, and thus it will be seen that by inserting 25 the key in the slot 30 of the barrel and causing the same to enter the slot 35 in the block 25, the flanges 39 may be caused to pass beneath the flanges 36 and into the segmental recesses 34, by turning the key to the right 30 and then by pulling outward on the key, the block will be correspondingly moved to disengage the portion 23 of the catch or bolt 21 from the slot 19 of the shackle. The spring 17 will then immediately act to open 35 the shackle, while in order to engage the shackle, it is simply swung against the action of the spring 17 into the slot 20 and the spring 24 will cause the engaging end portion or nose 23 to enter the slot 19, after the 40 beveled portion 18 has moved the catch or bolt 21 inwardly by engagement with the rounded or beveled nose portion thereof, and as the springs are made relatively strong, the lock will be securely held against spurious 45 opening.

From the foregoing description taken in connection with the accompanying drawings, it is thought that a clear and comprehensive understanding of the construction, 50 operation, and advantages of my invention may be had, and while I have shown and described the device as embodying a specific structure, I desire that it be understood that such changes may be made in said structure

as do not depart from the spirit and scope 55 of the invention as claimed.

Having thus described my invention, what I claim is new and desire to secure by Letters Patent, is:

1. In a padlock, a casing, a shackle pivoted at one corner of the casing and having an opening in its free end also engageable in the casing, a pivoted catch engageable with the opening of the shackle to secure the latter in locked position, means to normally hold said catch in said position, a block 60 slidable in the casing and connected to the catch, a barrel turnable in the casing and provided with a slot therethrough, means to limit the turning of the barrel, means to prevent displacement thereof longitudinally, said block being provided with a socket having a key receiving slot corresponding to the slot in the barrel, and undercut recesses communicating with the slot and 65 providing flanges adapted to receive a key having opposite extensions therebeneath whereby outward pull may be exerted upon the block for releasing the catch. 70

2. In a padlock, a casing, a shackle pivoted at one corner of the casing and having an opening in its free end also engageable in the casing, a pivoted catch engageable with the opening of the shackle to secure the latter in locked position, means to normally hold said catch in said position, a block slidable in the casing and connected to the catch, a barrel turnable in the casing and provided with a slot therethrough, means to limit the turning of the barrel, means to prevent displacement thereof longitudinally, said block being provided with a socket having a key receiving slot corresponding to the slot in the barrel, and opposite undercut recesses 80 providing flanges adapted to receive a key having opposite extensions therebeneath when said key is inserted in the slot and turned whereby outward pull may be exerted upon the block for releasing the catch, said slots 85 being of segmental formation whereby said flanges are engaged by turning the key in one direction only, the opposed sides of the slots being solid to prevent engagement of the key 90 beneath the flanges in the opposite direction. 95

In testimony whereof, I affix my signature 100 hereto.

FORREST D. LUCKEY.
